CATALYTIC CONVERSION OF
HYDROCARBONS

Roger S. Hovey, Bartlesville, Okla., assignor to
Phillips Petroleum Company, a corporation of
Delaware

Application August 27, 1945, Serial No. 612,961

9 Claims. (Cl. 260—666)

1

This invention relates to the conversion of hydrocarbons and especially of open-chain paraffins and cycloparaffins. More particularly it relates to the conversion of normal C₄ and higher paraffins to branched-chain C₄ and higher paraffins and to the conversion of methyl cyclopentane to cyclohexane. Where normal C₄ and higher paraffins are employed as the starting material, the principal or sole reaction may be simple isomerization to the corresponding isoparaffin or reactions may take place whereby the normal paraffin feed is converted to isoparaffins of lower and higher molecular weight in addition to the corresponding isoparaffin. For example, normal pentane may be converted to a mixture of isoparaffins including substantial or large proportions of isobutane and branched-chain hexanes in addition to isopentane. Likewise normal hexane may be converted to isobutane and isopentane in addition to branched-chain hexanes usually including neohexane, diisopropyl and methylpentanes. This type of conversion is termed reconstruction, disproportionation or "Isoversion." More specifically, the present invention relates to the conversion of hydrocarbons in the presence of a catalyst consisting of a major proportion of substantially anhydrous hydrogen fluoride and a minor proportion of titanium tetrafluoride.

The conversion of straight-chain or normal paraffins to the more valuable branched-chain paraffins in the presence of a catalytic body is a well-known reaction. One catalyst for these reactions known in the art is anhydrous aluminum chloride. By employing this catalyst per se in contact with a hydrocarbon material such as gas oil in a still operated at 400° F. and above, the hydrocarbon is cracked to produce gasoline boiling-range hydrocarbons of branched-chain character. By employing anhydrous aluminum chloride under less drastic conditions and/or in a form whereby its activity is modified, such as the fluid complex, isomerization of straight-chain hydrocarbons to branched-chain isomers may be carried out, the proportion of the feed stock converted to compounds of molecular weight different from that of the feed being controlled to such extent that high yields of desired products are obtained. Thus, branched-chain

2

isomeric hydrocarbons are obtained from charge stocks such as normal butane, pentane and the like. The splitting reactions whereby products of different molecular weight from that of the charge are produced may be reduced by conducting the reaction in the presence of a catalyst modifier such as hydrogen and/or naphthenic hydrocarbons.

It is also well-known that certain cycloparaffins are more valuable than other cycloparaffins. For example, cyclohexane has much greater value than methyl cyclopentane, large quantities of which are available from natural gas and gasoline. Accordingly, a simple and economical process for isomerizing the less valuable cycloparaffins to the more valuable cycloparaffins is of great commercial significance.

The principal object of the present invention is to provide an improved process for the conversion of hydrocarbons. Another object is to provide an improved process for the isomerization of normal C₄ or higher paraffins to the more valuable corresponding branched-chain paraffins. Another object is to provide an improved process for the reconstruction of C₄ or higher paraffins to form mixtures of branched-chain paraffins having four and more carbon atoms per molecule. Another object is to provide a process for the conversion of straight-chain relatively low octane number paraffins to the more valuable branched-chain paraffins. Another object is to effect the conversion of normal hexane to neohexane and diisopropyl in a simple and commercially feasible manner. Another object is to provide an improved process for isomerizing cycloparaffins, especially those having five and six carbon atoms in the ring. Another object is to provide an improved process of isomerizing methyl cyclopentane to cyclohexane. Another object is to provide a new catalyst which is especially adapted to the foregoing reactions but which may be used in other reactions for which it is suitable. Another object is to provide a novel and highly advantageous method of preparing the new catalyst. Another object is to provide a novel method of incorporating the new catalyst into a hydrocarbon participating in the conversion. Many other objects will more fully hereinafter appear.

The accompanying drawing which is self-explanatory portrays diagrammatically the hydrocarbon conversion process of the present invention in its more specific aspect wherein the catalyst comprises essentially a major proportion of hydrofluoric acid and a minor proportion of titanium tetrafluoride.

In accordance with the present invention a saturated hydrocarbon selected from the group consisting of paraffins and cycloparaffins, especially an isomerizable paraffin or cycloparaffin hydrocarbon having at least four and usually at least five carbon atoms per molecule, is converted by contacting with a catalyst comprising hydrogen fluoride and titanium tetrafluoride under conversion conditions. Usually conditions are so adjusted that the principal reaction or substantially the sole reaction is isomerization of the cycloparaffin to a more valuable cycloparaffin or isomerization of a normal C₄ or heavier paraffin to an isoparaffin or reconstruction of the normal C₄ or heavier paraffin to a mixture of isoparaffins including not only the corresponding isoparaffin but also isoparaffins of a different number of carbon atoms per molecule.

The process of the present invention is applicable to effect the isomerization or reconstruction of C₄ and heavier paraffins or the isomerization of a cycloparaffin having 5 or 6 carbon atoms in the ring. The isomerization of paraffins is usually conducted in such manner that a normal paraffin is converted to a corresponding branched-chain paraffin, although since isomerization is an equilibrium reaction it may be applied to effect the reverse reaction, namely, conversion of a branched-chain paraffin to the corresponding straight-chain form in the exceptional situation where such a conversion is desired. Likewise, while the process of this invention is usually employed to convert a less valuable alkyl cyclopentane to a more valuable cyclohexane derivative, particularly methyl cyclopentane to cyclohexane, it may be employed to effect the reverse reaction.

I have discovered a new catalyst comprising essentially a major proportion of anhydrous hydrofluoric acid and a minor proportion of titanium tetrafluoride which is effective in the conversion of straight-chain hydrocarbons to the more valuable branched-chain hydrocarbons and in the isomerization of cycloparaffins, as for example, the isomerization of methyl cyclopentane to cyclohexane. The proportion of titanium tetrafluoride contained in the catalyst may range from about one up to twenty weight per cent of the hydrogen fluoride and titanium tetrafluoride, or higher, if desired, although usually it will not be desirable to use more than will go into solution in the acid phase under reaction conditions, although solutions may be used, if desired, that contain TiF₄ in excess of that held in solution.

The following example will facilitate a more complete understanding of my invention. This example is not, however, to be interpreted to place any limitation on this invention.

Example

To a 1.6 liter monel bomb was charged 30 g. of TiF₄, 520 g. of anhydrous hydrogen fluoride, and 520 cc. (approximately 343 g.) of normal hexane, this volume being measured at room temperature. The bomb was shaken for one hour at a temperature of 209° F. The content of the bomb was then removed and the hydrocarbon phase recovered

and freed of catalyst. An analysis of the hydrocarbon product yielded the following results:

Component	Weight per cent
Propane	0.8
Isobutane	9.9
Normal butane	0.7
Isopentane	9.7
Normal pentane	0.6
Neohexane	11.1
Diisopropyl	
2- and 3-methylpentane	29.3
Normal hexane	20.6
Heavier	17.3
	100.0

For comparison, the following experiment was carried out:

To a 2880 cc. stainless steel bomb a charge of 995 cc. of normal hexane and 1000 cc. of anhydrous hydrofluoric acid were added. The bomb was agitated for three hours at 291° F. The recovered hydrocarbon consisted of 83.5 weight per cent normal hexane and 16.5 weight per cent of isomeric hexanes.

A comparison of the hydrocarbon product of these two experiments shows the effective promoting action of the titanium tetrafluoride and the superior catalytic properties of this new catalyst.

Other paraffins, including butane, pentane, heptane, and heavier as well as hexane may be isomerized with this catalyst.

In addition to the isomerization of the paraffin hydrocarbons, this new catalyst is effective in accomplishing the isomerization of naphthenic hydrocarbons. Illustrative of this type of isomerization is the conversion of methyl cyclopentane to cyclohexane.

In carrying out conversions with this catalyst, the preferred conditions of reactions are: contact time, five minutes to three hours; temperature, 70 to 450° F.; pressure, sufficient to maintain substantially liquid phase; and the catalyst-to-hydrocarbon ratio between 4:1 and 1:4, on a volume basis.

In the event that the production of the compounds of higher and lower molecular weight than the charge stock is not desired, the production of these compounds may be inhibited by conducting the reaction in the presence of hydrogen in the proportion of one to twenty atmospheres partial pressure when measured at room temperature, the exact amount depending upon the paraffin treated. Naphthenic hydrocarbons, for example, methyl cyclopentane and cyclohexane, or aromatic hydrocarbons in the proportion of one to twenty-five weight per cent of the charge, may also be used to inhibit the splitting reactions when conversion of paraffins is practiced.

Numerous types of apparatus are suitable for carrying out hydrocarbon conversion on commercial scale using this catalyst and are known to those skilled in the art. Mechanically-agitated or jet-agitated contactors may be used, or the hydrocarbon may be dispersed and allowed to rise through a body of the catalyst. Intimate contacting of the catalyst and hydrocarbon is desirable.

Continuous operation may be practiced in the following manner: The hydrocarbon to be processed is charged to a contactor containing the catalyst. Here the catalyst and hydrocarbon are mixed, and an emulsion of catalyst and hydro-

carbon removed from the mixer to a gravity settler. In the settler, the emulsion separates to form a hydrocarbon phase in the upper portion of the settler and catalyst phase in the lower portion. The catalyst phase is recycled to the reactor, and the hydrocarbon phase is removed and processed for product recovery, the separation of the various products and recycle streams being accomplished by distillation.

In such a system, the titanium tetrafluoride is readily added to the catalyst by pumping $TiCl_4$, a liquid, in the desired amount into the catalyst recycle stream or into the hydrocarbon feed stream, in which $TiCl_4$ is soluble. The $TiCl_4$ reacts when in contact with HF, which is in liquid phase, to form TiF_4 , which goes into solution in the HF as rapidly as it is formed. An alternative method of addition involves placing the previously manufactured titanium tetrafluoride in a closed vessel and passing the catalyst recycle stream through this vessel to saturate the stream with TiF_4 .

It may also be desired to add water in proportions ranging from a trace (0.01) up to about 0.1 weight per cent in the charge to the reactor in order to reduce sludge formation.

The conditions best suited to carrying out reactions with this catalyst vary with the particular hydrocarbon or mixture of hydrocarbons to be processed, but these conditions may readily be determined by trial.

In use the catalyst gradually loses activity. Such spent or partially spent catalyst may be regenerated in any desired manner, as for example, by distilling off HF and other products and recovering TiF_4 from the residue by extraction, sublimation or the like.

I claim:

1. A process for the conversion of a saturated hydrocarbon selected from the group consisting of isomerizable paraffins and cycloparaffins having at least 5 carbon atoms in the ring which comprises passing a hydrocarbon from said group substantially free of unsaturates into contact with a liquid catalyst comprising essentially a major proportion of hydrogen fluoride and a minor proportion of titanium tetrafluoride dissolved therein and in which the titanium tetrafluoride is in an amount within the range of from 1 to 20 per cent by weight of said catalyst under reaction conditions so as to effect substantial reconstruction of said hydrocarbon.

2. The process of claim 1 wherein sludge formation during the reaction is reduced by having water present in proportions ranging from 0.01 to 0.1 weight per cent of the hydrocarbon charge.

3. A process for isomerizing methyl cyclopentane to cyclohexane which comprises contacting said methyl cyclopentane substantially free of unsaturates with a catalyst consisting of a major proportion of hydrogen fluoride and a minor proportion of titanium tetrafluoride dissolved therein, said titanium tetrafluoride being present in an amount within the range of from 1 to 20 per cent by weight of said catalyst, under conditions such that isomerization of said methyl cyclopentane to cyclohexane is the principal reaction.

4. A process for the conversion of a saturated hydrocarbon selected from the group consisting of isomerizable paraffins and cycloparaffins which comprises contacting said saturated hydrocarbon substantially free of unsaturates with a catalyst comprising essentially hydrogen fluoride having dissolved therein from 1 to 20 per cent by weight

of titanium tetrafluoride based on the weight of said catalyst, the volume ratio of said catalyst to said hydrocarbon being within the range of from 4:1 to 1:4, under pressure sufficient to maintain liquid phase and at a temperature of from 70 to 450° F. for a time of from 5 minutes to three hours so as to effect conversion of said hydrocarbon to other saturated hydrocarbon.

5. A process for the isomerization of a saturated hydrocarbon selected from the group consisting of isomerizable paraffins and cycloparaffins which comprises contacting said saturated hydrocarbon in substantial absence of olefins with a catalyst consisting of hydrogen fluoride having dissolved therein from 1 to 20 per cent by weight of titanium tetrafluoride based on the weight of said catalyst, the ratio of said catalyst to said hydrocarbon being within the range of from 4:1 to 1:4 by volume, under pressure sufficient to maintain liquid phase and at a temperature of from 70 to 450° F. for a time of from 5 minutes to three hours so as to effect isomerization of said saturated hydrocarbon to an isomer as a principal reaction of the process.

6. A process for the reconstruction of a paraffin hydrocarbon having at least four carbon atoms per molecule which comprises contacting said paraffin hydrocarbon in substantial absence of olefins with a catalyst comprising essentially hydrogen fluoride having dissolved therein from 1 to 20 per cent by weight of titanium tetrafluoride based on the weight of said catalyst, the ratio of said catalyst to said hydrocarbon being within the range of from 4:1 to 1:4 by volume under pressure sufficient to maintain liquid phase and at a temperature of from 70 to 450° F. for a time of from 5 minutes to three hours and thereby effecting reconstruction of said paraffin hydrocarbon as a principal reaction of the process.

7. A process for the reconstruction of normal hexane which comprises subjecting a reaction mixture consisting of approximately 343 parts by weight of normal hexane, approximately 520 parts by weight of anhydrous hydrogen fluoride and approximately 30 parts by weight of titanium tetrafluoride dissolved therein in a closed vessel in the substantial absence of olefins to a temperature of approximately 209° F. for approximately one hour and thereby effecting reconstruction of said normal hexane to branched-chain hexanes including substantial proportions of each of neohexane and diisopropyl, to isobutane in substantial proportion, to isopentane in substantial proportion and to hydrocarbon heavier than hexane in substantial proportion.

8. A process for the isomerization of an isomerizable paraffin hydrocarbon having at least 4 carbon atoms per molecule which comprises passing said paraffin hydrocarbon substantially free of olefins into contact with a liquid catalyst comprising essentially a major proportion of hydrogen fluoride and a minor proportion of titanium tetrafluoride dissolved therein and in which the latter is present in an amount within the range of from 1 to 20 per cent by weight of said catalyst under reaction conditions which effect substantial isomerization of said paraffin hydrocarbon.

9. A process for the isomerization of normal hexane which comprises contacting normal hexane in the substantial absence of olefins with a liquid catalyst comprising essentially a major proportion of hydrogen fluoride and a minor proportion of titanium tetrafluoride dissolved therein and in which the latter amounts to from 1 to 20 per cent of the catalyst mixture under

7
reaction conditions of time, temperature, and pressure regulated so as to effect substantial isomerization of normal hexane as the principal reaction of the process.
